(57) **CLAIM**

The ornamental design for a multiport USB hub, as shown and described.

DESCRIPTION

FIG. 1 is front elevational view of a multiport USB hub for a computer showing our new design; FIG. 2 is a rear elevational view thereof; FIG. 3 is a left side elevational view thereof; FIG. 4 is a right side elevational view thereof; FIG. 5 is a top plan view thereof; FIG. 6 is a bottom plan view thereof; and FIG. 7 is a front, top, left perspective view thereof; and FIG. 8 is a rear, bottom, right perspective view thereof. The broken lines represent portions of the structure that forms no part of the claim.

1 Claim, 8 Drawing Sheets
